LIQUID FLOW CUTOFF AND TIMER

Henry A. Erikson, Coral Gables, Fla.

Application March 8, 1950, Serial No. 148,307

5 Claims. (Cl. 137—675)

1

This invention relates generally to devices for terminating the flow of liquid passing through a liquid supply line and particularly concerns such devices which operate automatically after a predetermined amount of the liquid has passed through the line.

My invention is similar in nature to that disclosed in my abandoned application for patent Serial No. 118,379, filed September 28th, 1949. However, the presently considered device does away with the chamber float described in that application and accomplishes the flow cut-off functions through pressure of the liquid itself.

A liquid flow cut-off and timer is useful in connection with a fluid conductor wherever it is desirable to cut-off the flow after a predetermined time period has lapsed. An example would be its use in connection with a lawn sprinkling system to conveniently and economically limit the watering of a particular area to a desired period of time.

It is accordingly the primary object of my invention to provide a liquid flow cut-off mechanism which is actuated by pressure of a portion of liquid itself.

Another object of my invention is to provide a mechanism adapted to terminate the flow of liquid through a conductor after a predetermined period of time, and having means allowing the length of said time period to be selectively varied.

With these and other objects in view, the invention broadly embodies a liquid pressure chamber adapted for connection at a point along a fluid supply line, means for allowing a small portion of the liquid to enter the chamber whereby fluid pressure is built up in the chamber, and means whereby said chamber pressure is made operative to move a valve member into the main path of liquid flow to cut off the flow through the supply line.

The above mentioned and still other more particular objectives will be disclosed in the course of the following specification, reference being made to the accompanying drawing in which—

Fig. 1 is a view in vertical section showing the cut-off valve in an open position and with its closed position denoted by broken lines.

Fig. 2 is a side elevational view of the valve mechanism.

Fig. 3 is a fragmentary vertical section showing a modified form of the valve mechanism.

Fig. 4 is a fragmentary section of the view shown in Fig. 1 with the valve member 36 removed.

Referring now more particularly to the draw-

ing and by reference characters the liquid pressure chamber, shown generally at 4, is formed of an upright tubular member 5 having top and bottom caps 6 and 7 respectively threaded over the ends thereof to form a cylindrical receptacle. The bottom cap 7 is rigidly mounted on a base or standard 8 to support the receptacle in a vertically extending position. Chamber 4 is associated with the fluid supply line through a connecting structure formed by the various fittings 9-12 inclusive. The numeral 9 denotes an externally threaded neck member which is threaded through a central opening in the cap 6 to extend upwardly therefrom. A cross fitting 10 is threaded over the upper end of the neck member 9 with the lateral arms thereof retaining the short nipple pieces 11 and 12 which extend horizontally for connection at their outer ends with terminal couplings (not shown) on the separated sections of a fluid supply line. It will be observed that the fitting 10 also serves as a housing for the flow cut-off valve to be subsequently described.

The upper coupling arm of the member 10 is fitted with a head plug 13. This plug and the member 9 have diametrically small central passages 14 and 15 respectively which extend in vertical alignment with each other. The inner opposing faces of the two members are similarly formed by being centrally recessed as at 16 and 17 to form opposing round seats in each of which the bottom wall tapers to the respective member passage 14 or 15. The upper end of the passage 14 is enlarged and internally threaded to receive the open externally threaded end of a small cylindrical chamber member 18. A drain tube 19 is connected as at 20 to a side wall of the chamber 18 to carry fluid therefrom.

I provide a liquid flow cut off mechanism to operate principally within the member 10. This mechanism comprises a valve actuating member, shown generally at 21 and a ball valve 26. The construction of the valve actuating member can perhaps be best understood by referring to Fig. 2. A substantially oval shaped stirrup 22 is formed of a relatively narrow strip of material with a somewhat wider portion 23 at the bottom thereof, and with thin elongated stems 24 and 25 extending vertically from the top and under sides thereof. It will be observed that when the mechanism is placed within the member 10 the stems 24 and 25 extend through the passages 14 and 15 respectively. The stems are only slightly smaller diametrically than the passages in which they move restricting the same so as to allow only a very small amount of liquid to pass through the

passages. A ball valve 26 fits loosely within the stirrup 22 to rest upon the portion 23. When the mechanism is set in position the stirrup sets in the seat formed by the recess 16 in the upper end of the neck member 9 with the ball valve 26 retained in the stirrup by the annular top face of the member. It will be readily realized that if the member 21 is moved upwardly it will carry the ball 26 with it, and that with the passages 14 and 15 serving as guideways for the stems 25 and 24 such movement is restricted to a set vertical path. An annular valve seat 27 is formed at the inner end of the outlet nipple 11 and is adapted to receive the ball valve 26 and provide a fluid tight seal therewith.

Referring now back to the chamber 4, it may be observed that I provide the side wall of the chamber with a top pressure relief outlet 28 and a plurality of vertically spaced lower drain ports 29. These ports are disposed similarly to those disclosed in my aforementioned application. However, I have here provided the outlet 28 with a two-way valve 30 and the lower ports 29 with pet cocks 31 to facilitate opening and closing the same. The valve 30 is operated by a handle 32 and has a connection as at 33 with the drain tube 19. The valve has inner ports 34 and 35 which can be selectively moved, through manipulation of the handle 32 to expose the interior of either the chamber 4 or the chamber 18 to the outside atmosphere. Thus when the handle 32 is in an outwardly extending position fluid in chamber member 18 and tube 19 may drain freely out through the valve port 34 while the port 26 is sealed. If, on the other hand, the handle is turned to extend downwardly the chamber 4 is opened to the atmosphere through the valve ports 34 and 35.

I provide an air outlet valve in the top cap 6 of the pressure chamber. This valve comprises a tubular vent 36 extending through the top wall with a needlelike valve member 37 disposed loosely in the vent and having an enlarged buoyant head 38 adapted to seal the vent when moved against the inner end thereof. Near the top of the chamber 4, I also provide a port 39 having a bypass valve 40 which connects with the interior chamber 41 of the member 10 through tube 42. The valve handle 43 is operative to open and close communication between the two chambers and is shown in Fig. 1 in closed position.

Turning now to the operation of my invention it will be observed that as liquid under pressure is admitted to the device through the supply line connected conduit or nipple 12, it will pass through the valve chamber 41 and out through the nipple 11 to the sprinkler system or the like attached thereto. Small portions of the liquid however, will pass upwardly through the passage 14 and downwardly through the passage 15. The liquid which is forced upwardly into the chamber 18 is free to drain out through the tube 19 and valve 30. However, the liquid portion which is forced downwardly through the passage 15 is caught in the chamber 4. As the level of the liquid rises within the chamber the air displaced escapes through the vent 36 at the top thereof until the liquid engages the head 38 and floats it against the vent. The chamber is then completely sealed with the exception of the restricted passage 15 and when the chamber is full with the liquid the liquid pressure within the chamber 4 equalizes with that in the chamber 41. With the increased liquid pressure in the chamber 4, wherein projects the lower end of the stem 24, 75

and with the chamber 18, wherein projects the upper end of stem 25, being open to the atmosphere the actuating member 21, carrying the valve ball 26, is caused to move upwardly by fluid pressure on the lower end of stem 24 until the stem 25 contacts the top wall of the member 18. As the ball is moved into the main liquid flow it is caught by the flow and moved against the valve seat 27 cutting off the supply of liquid to the nipple 11 and points beyond. The valve mechanism is then disposed as shown in broken lines in Fig. 1.

The member 21 may then be lowered by moving the handle 32 of the valve 30 to a downwardly extending position whereupon chamber 4 is opened to the atmosphere and the chamber 18 is closed. This causes the liquid pressure in chamber 18 to rapidly equalize with that in the valve chamber and move the member 21 back down to its seated position. This downward movement of the member 21 by pressure is frequently desirable because one of the stems 24 or 25 might stick in its respective passage due to friction, dirt or the like. It will be observed that the stirrup 22 is so formed 25 that it can be lowered without moving the ball valve 26 from its cutoff position.

By cutting off the main supply of fluid to the device the ball 26 will then gravitationally reseat itself in the stirrup 22 as the pressure in chamber 4 diminishes. Due to the restricted clearance through the opening 15 the pressure reduction is very slow. To hasten this reduction and the dropping of the ball 26, I provide the bypass valve 40 which is opened by moving handle 43 to a downwardly extending position to open the chamber 41 to the atmosphere through the valves 49 and 39. The pressure in 41 is accordingly relieved quite abruptly and the valve opens without delay. By readjusting the valves 30 and 40 to their original positions and draining the chamber 4 through one of the petcocks 31 the device is then ready for another fluid cycle. The period of time to elapse before the valve mechanism is actuated to cut off the flow is, of course, dependent upon the liquid level in the chamber at the time the flow through the device is commenced. The liquid level is in turn governed by the petcock 31 used to drain the chamber of its preceding fill. As taught in my aforementioned application for patent, any number of the ports 29 may be used in vertically spaced relation in order to allow selective regulation of the cut-off operation after the lapse of any one of a number of varying periods of time. The chamber 4 may be initially filled to any desired level by opening both the petcock adjacent that level and the valve 40 after the main fluid supply has been turned on.

It is found that the air vent at 36 may be omitted entirely from the device as illustrated in Fig. 4 without rendering it inoperable. However, by expelling the air from the chamber to make valve actuation dependent solely upon liquid pressure the valve is raised to its cut-off position more abruptly.

Referring now to Fig. 3, a slight modification of my invention is shown wherein I use a gate or flap valve in place of the ball valve of the preferred construction. There the gate 44 is hinged along its bottom edge as at 45 to the inner end face of the conduit 11 for opening and closing movements thereover. The stirrup 22, shown in vertical section, has an upwardly projecting member 46 mounted rigidly between the sides thereof to support the gate 44 in a substantially

horizontal open position. It will be readily recognized that as the member 21 is forced upwardly by the same liquid pressure action as described in connection with the preferred embodiment, the gate 44 will be swung upwardly about its hinge 45 until it is caught in the main liquid flow and moved against the end of the outlet nipple 11.

I have thus provided a new and improved mechanism for economically and efficiently carrying out the aforementioned objectives. It is understood that suitable modifications may be made in the structure as disclosed, provided such modifications come within the spirit and scope of the appended claims. Having now therefore fully illustrated and described my invention, what I claim to be new and desire to protect by Letters Patent is:

1. A device for terminating the flow of liquid through a liquid supply line which comprises a valve chamber adapted for connection at an intermediate point on the supply line carrying liquid under pressure so that the liquid will pass therethrough, a liquid pressure chamber connected to the valve chamber and having a restricted passage therebetween for transmitting a small portion of the liquid to the pressure chamber, a wall of said valve chamber having an opening to the atmosphere, a valve mechanism disposed within the valve chamber and having an actuating portion extending through said passage and into the pressure chamber, a portion of said mechanism extending outwardly through said opening to the atmosphere, said opening being greatly restricted whereby as the pressure chamber is filled the liquid pressure therein will equalize with the pressure in the valve chamber to move the valve mechanism outwardly of said pressure chamber and toward said opening, and said mechanism having means for cutting off the liquid flow as it is so moved.

2. In a liquid flow cut-off device for automatically terminating the flow of liquid passing under pressure therethrough, a pair of liquid pressure chambers, a valve housing disposed intermediate the pressure chambers and connected therewith, said valve housing having both a liquid inlet and a liquid outlet passage, means allowing a small portion of the liquid introduced through said inlet passage under pressure to enter each of the pressure chambers whereby as said chambers become filled the liquid therein will be held under pressure, means for selectively opening each of said chambers to the atmosphere to relieve said pressure, and a liquid cut-off mechanism disposed within said valve housing and adapted to open and close said outlet passage, said valve mechanism comprising a valve member and a valve actuating member for carrying the valve member and slideably projecting into each pressure chamber to slide between valve opening and valve closing positions, said actuating member being responsive to the pressure in the filled chamber to slide toward the open pressure chamber.

3. In a liquid flow cut-off device for automatically terminating the flow of liquid passing under pressure therethrough, a pair of liquid pressure chambers, a valve housing disposed intermediate the pressure chambers and connected therewith, said valve housing having both a

liquid inlet and a liquid outlet passage, means allowing a small portion of the liquid introduced through said inlet passage under pressure to enter each of the pressure chambers whereby as said chambers become filled the liquid therein will be held under pressure, means for selectively opening each of said chambers to the atmosphere to relieve said pressure, and a liquid cut-off mechanism disposed within said valve housing and adapted to open and close said outlet passage, said valve mechanism comprising a valve member and a valve actuating member for carrying the valve member and slidably projecting into each pressure chamber to slide between valve opening and valve closing positions, said actuating member being responsive to the pressure in the filled chamber to slide toward the open pressure chamber, and said means for selectively opening each of said chambers comprising a single control valve associated with both pressure chambers for selectively opening either chamber to the atmosphere.

4. A device for cutting off the flow of liquid in a liquid supply line carrying liquid under pressure after a predetermined amount has been supplied which comprises a liquid measuring chamber, means for connecting the chamber to the supply line so as to allow a constant portion of the liquid to enter the chamber, said chamber having an air vent at the top thereof for allowing escape of the air displaced by the liquid entering the chamber, means responsive to the liquid level for closing said vent as the chamber is filled with the liquid so as to hold said chamber liquid under pressure, a valve means associated with the chamber and responsive to pressure in the chamber to cut off the liquid flow in the supply line, and means for draining the liquid in said chamber to any selected level.

5. A device for automatically terminating the liquid flowing under pressure from a supply source after a predetermined amount has flowed which comprises a valve chamber having an inlet passage for connection to the supply source and an outlet passage, a liquid receptacle connected to the valve chamber and having a restricted passage therebetween allowing a small portion of the fluid entering the valve chamber to pass into the receptacle, said receptacle being otherwise sealed from the atmosphere whereby when the receptacle has filled the liquid pressure therein will rise to equal the pressure in the valve chamber, a valve mechanism disposed within the valve chamber and responsive to said equalization in pressure to close said outlet passage, and said receptacle having a plurality of vertically spaced drain cocks in a side wall thereof for draining the liquid in the receptacle to any selected one of a plurality of levels.
